UNITED STATES PATENT OFFICE.

JOSEPH E. RELLER AND WILLIAM KRECKER, OF LONG BEACH, CALIFORNIA; SAID KRECKER ASSIGNOR TO SAID RELLER.

CAN OPENER AND SEALER.

1,416,577.

Specification of Letters Patent. Patented May 16, 1922.

Application filed February 25, 1920. Serial No. 361,337.

To all whom it may concern:

Be it known that we, JOSEPH E. RELLER and WILLIAM KRECKER, citizens of the United States, residing at Long Beach, in the county of Los Angeles and State of California, have invented new and useful Improvements in Can Openers and Sealers, of which the following is a specification.

This invention relates to container and can receptacle punches and closing means, and the invention has for its object to provide a simple, inexpensive, substantial, practicable, durable and effective device to secure the punching of the tops of metallic containers such, for instance, as metallic milk cans so as to provide a pouring aperture and a vent aperture in the punctured end of the can, and further to provide such a device that will be serviceable to close the apertures after they have been made. The invention consists of the punching and closing device a form of which is illustrated in the accompanying drawings and described and claimed herein.

Figure 1 is a perspective of a can to which the device is shown as applied in puncture closing position.

Fig. 2 is a side elevation of the can with its upper portion in section and showing the punching and closing device in place.

Fig. 3 is an underneath perspective of the improved device showing a can in dotted line relation.

The device consists of a rigid and, preferably, metallic plate or body portion 2 of any suitable length and width and shape, in plan, and the plate is provided adjacent one end with downwardly extending guide forming and positioning tongues or lugs 3 intermediately between which there is provided an extending eye part 4, preferably, integrally formed of the sheet material of which the body 2 is made; the eye or ring part 4 being shown as in the plane of the body part 2. The part 4 forms both a handle by which the device may be conveniently manipulated and also enabling it to be suspended as from a hook or nail when not in use.

The downwardly extending tongues or lugs 3-3 are set in angular position in the arc of a circle of indeterminate radius so that when the device is applied with the tongues 3-3 adjacent the upper corner of

a can C there will then be positioned above 55 the top of the can a plurality of impaling or puncturing teeth one of which is shown at 5 as arranged adjacent to the end of the plate 2 that is provided with the guide tongues 3-3 so that this point 5 will occupy 60 a position on the top T of the can adjacent to the edge of the top. The other impaling or puncturing prong designated 6 is positioned beyond the point 5 at such position as to make an aperture that will be exposed 65 by the tilting of the can to permit the inflow of air, and the fluid contents of the can may be poured out of the hole formed by the tooth or punch 5 when the punching device has been removed from the can. 70

These punching teeth 5-6 may be provided and arranged in any suitable manner and number, and as here shown consist of conical hardened steel prongs riveted as at 7 in perpendicular position on the lower 75 side of the plate part 2.

When the top of the can is to be punctured the tongues 3-3 are adjusted against the upper corner of the can and this will arrange the punches 5-6 in a diametrical 80 line on opposite sides of the center of the top, and by the application of necessary pressure the punches will be forced through the top T and may be driven down until the plate 2 is in close juxtaposition to the top T 85 at which time the annular shoulders 8 about the bases of the punches 5-6 will rest on the contiguous portion of the top about the apertures made.

To draw the contents of the can the 90 punches are withdrawn and after the content has been discharged from the can as may be desired the punches can again be applied to fill the apertures, when the shoulders 8-8 will form tight closures for 95 the openings.

By this device all of the holes may be punched simultaneously by a blow or pressure upon the punching means or the punches may be pressed in by pressure on 100 either end of the device successively.

Various changes may be made without departing from the spirit of the invention as claimed.

What is claimed is:

A can puncturing and puncture closing device, comprising a plate, a pair of puncturing members projecting from the under

side of said plate, a pair of spaced ears formed integral with and depending from one end of said plate to facilitate the positioning of the device on a can, and a per-
5 forated member projecting from the end of the plate between said ears, which perforated member provides means whereby the device

may be suspended from a suitable support while not in use.

In testimony whereof we have signed our 10 names to this specification.

JOSEPH E. RELLER.
WILLIAM KRECKER.
